5 Claims. (Cl. 22—10)

1

This invention relates to coremaking machines and particularly to machines for making sand cores.

Heretofore it has been common practice to use core making machines of the "roll-over" type which inherently require tiring manual operations as well as many adjustments to accommodate changes for core-boxes of different sizes. The operator must move from one position to another and frequently lift and roll the heavy core-box table in the operation of moving the core-box from one position to another. These and other characteristics of such prior types of machine are undesirable not only because of the conditions which impose operator fatigue but the limitations as to time per operation and time for changing from one job to another.

Our invention aims to provide a generally improved core-making machine characterized by novel structural features which make for time and energy saving while maintaining a high degree of uniformity and perfection in the resultant cores.

In furtherance of this general object our invention contemplates the provision of a machine so constructed that the operator does not have to walk around but completes all coremaking operations from one position directly in front of the machine and he is not required to perform lifting and other work operations in a stooped or bent over position. One of the features of our invention is a pivotally mounted beam carrying at one end a base assembly for the core-box and at the opposite end a head assembly including a fluid operated plunger and clamping head for automatically clamping and unclamping the core-plate and box in response to simple and easy manual control operations. These assemblies are so arranged on the pivoted beam as to provide a balanced structure which requires a minimum of effort to operate.

Another object of our invention is to provide a fluid operated clamping and drawing device together with a self-adjusting equalizer which acts against the core-plate to insure positive positioning and clamping thereof under varying conditions and also insures steady and straight drawing of the sand core from the core-box.

Another object is to provide a clamping and drawing device which compensates for variations in thickness of core-plates and core-boxes within a substantial range, thus eliminating time and attention to making set ups and adjustments within such range.

Another object is to provide a novel valve con-

2

trol for a fluid operated clamp and draw type coremaking machine.

A further object is to provide a machine characterized by a novel combination of features which give new results in core-making.

Other objects and attendant advantages will be appreciated by those skilled in this art as the invention becomes better understood by reference to the following description when considered in connection with the accompanying drawings, in which—

Figure 1 is a front elevation of a coremaking machine embodying our invention, showing the parts in the starting position;

Figs. 2 and 3 are top views, Fig. 2 showing the plunger head assembly swung to the open position as in Fig. 1 and Fig. 3 showing said assembly swung to the operating position;

Fig. 4 is a front elevation of the machine with the plunger head operated to clamp the core-box and with some of the top parts shown in section;

Fig. 5 is a front elevation of the machine with the beam assembly swung to the position opposite from Fig. 4 and with the core withdrawn from the core-box;

Fig. 6 is a side elevation of the machine in the position shown in Fig. 4;

Fig. 7 is an enlarged vertical section through the cylinder and valve taken substantially on the section line 7—7 of Fig. 4;

Fig. 8 is a further enlarged section lengthwise through the valve taken substantially on the section line 8—8 of Fig. 7;

Figs. 9 and 10 are cross-sections taken substantially on the section lines 9—9 and 10—10 of Fig. 8;

Fig. 11 is an enlarged detail section taken on the section line 11—11 of Fig. 4; and

Fig. 12 is a section on a reduced scale taken on the section line 12—12 of Fig. 8.

In the drawings we have shown an illustrative embodiment of our invention, the general assembly being best seen in Figure 6. A main beam

15 pivotally mounted at its center to turn about a horizontal axis is equipped at one end with a base assembly designated generally by 16 on which a core-box is clamped and at the other end with a head assembly designated generally by 17 which carries a cylinder and plunger for performing the

clamping and drawing operations and an air valve device for controlling these operations.

The beam is carried on a trunnion 18 which in turn is journaled in bearings 19 on a suitable frame structure 21. The beam may be swung

freely 180° in a counterclockwise direction from

the clamping position shown in Figure 4 to the drawing position shown in Figure 5, and 180° in a clockwise direction back to the starting position. Because of the distribution and balance of weight these operations may be easily performed by hand, it being observed that suitable stops 22—23 on the ends of the beam coact with a stationary stop 24 to limit the described positions of the beam.

The base assembly comprises a lower supporting bracket 25 clamped to and adjustable lengthwise on the beam and carrying a horizontal base 26 on which a core-box 27 is removably mounted. The core-box has a dovetail 28 on its underside extending from front to back and fitting between a fixed dovetail member 29 and dovetail clamps 31 which are carried on the base, each clamp 31 being movable by a screw 32 for clamping the core-box in working position and for releasing it when changing from one core-box to another.

The head assembly comprises an upper supporting bracket 33 also clamped to the beam but adjustable lengthwise thereon and carrying a cylinder 34 on an axis parallel with the beam. The cylinder is mounted on the bracket 33 to swing horizontally about a vertical pivot pin 35 between an open position shown in Figures 1 and 2 and a working position shown in Figures 3, 4, and 6. A stop 36 limits the cylinder in the working position. A spring 37 is arranged to yieldingly holds the cylinder either in the open or the closed position by acting at opposite sides of the pivot pin 35, as will be obvious from Figures 2 and 3. A piston plunger 38 having a piston head 39 in the cylinder is equipped at its lower end with spherical socket members 41 and 42 shaped to fit a ball member 43 which is fixed to an equalizing plate 44. By means of a hand screw 45 the socket members are clamped to the ball member with sufficient friction to permit universal movement of the plate 44 for self-adjustment of this plate when it is clamped down against a core-plate 46 by action of the plunger under air pressure applied in the cylinder against the top of the piston. The plate 44 has on its under face three equally spaced fingers 47a which equalize the contact against the core-plate and coact with the universal action of the ball and socket connection to give the self-adjusting and equalizing actions described.

The plunger is moved downwardly under fluid pressure in a clamping operation and also in the opposite direction under fluid pressure in a drawing operation but at a different rate of motion. These operations are under control of a valve device for controlling the fluid pressure. We prefer to use air pressure because it is common in foundries to provide air pressure equipment. Referring particularly to Figures 7, 8, 9, 10, and 12, we have provided a rotary tapered valve 47 fitting in a casing 48 which is supported by pipes 49 and 51 which in turn have suitable connections to opposite ends of the cylinder 34. A compression spring 52 holds the valve seated and the valve may be moved rotatively by means of a hand lever 53 fixed to its opposite end. Movement of the lever and consequently the valve is limited by a stop member 54 on the valve movable between stops 55 and 56, Figure 12, thereby directing the flow of air through the valve and to opposite sides of the piston. The rate of movement of the piston and plunger is controlled by the size of different exhaust openings, as will be presently described. Movement of the plunger upwardly is limited by a stop collar 57 which contacts one end of the cylinder as shown in Figure 7. The piston rod or

plunger extends through suitable bearings at each end of the cylinder and the upper end of the rod is equipped with a guide member 58, Figures 4 and 11, which slides in a slot in a guide member 59 fixed to the cylinder, thus maintaining the piston and the plate clamping head against rotative displacement. A suitable dust and dirt proof cover 61 encloses the guide end of the cylinder. Air under pressure is delivered to the cylinder through pipe 62 and a flexible hose connection 63 which connects with the low pressure side of an air supply line. The air pressure is supplied to the machine through a pipe line 64 which passes centrally through the trunnion 18, as shown in Figure 6, and out through the beam at 65, as shown in Figures 1 and 6. From 65 the pressure line branches at 66 to a reduced pressure line 67 which connects with the hose 63 and to a high pressure line 68 in the form of a flexible hose which connects to a conventional vibrator 69 fixed to the supporting bracket 25, as shown in Figure 1. This vibrator, under control of a hand valve 71, serves to give small rapid impulses to the core-box when drawing the core, this being a function well known in the art. The low pressure side of the air line has a pressure regulator 72 and a pressure indicator 73, best shown in Figure 1, to provide a pre-determined pressure.

Referring to the valve device, Figures 7 and 8, it will be observed that constant air pressure enters the casing at 62, and that this air inlet is in constant communication with an annular port 74 in the face of the valve. Port 74 communicates with a valve passage 75—76—77; and by rotative movement of the valve rotor passage 77 connects the air pressure either to the pipe 51, as shown in Figures 8 and 9, or to the pipe 49 as shown in Figure 10. The valve rotor is also provided on its face with an L-shaped port 78 which has a larger exhaust opening 81 to allow full exhaust of the air during the clamping operation. The valve rotor is also provided on its face with a port 82 designed to communicate the pipe 49 with an exhaust port 83 which has a small or restricted exhaust opening 84 for controlling exhaust of the air during the core drawing operation.

Operation of the machine will now be described: The starting position is shown in Figure 1 with the plunger head swung to the open position. The operator fills the core-box with core sand and levels off the top of the box according to known coremaking practice. The core-plate 46 is then positioned on top of the core-box. The operator then swings the plunger head forward from the open position shown in Figure 2 to work position shown in Figure 3, thus placing the head or pressure plate 44 in position to clamp the core-plate. The operator then moves the hand valve 53 down from the horizontal position shown in Figure 12 to the lower vertical position limited by the stop member 54 engaging the stop 55. This moves the valve rotor 47 clockwise from the position shown in Figure 9 to Figure 10, thereby connecting the air pressure port 77 with the pipe 49 and the upper end of the cylinder and causing the piston to be moved downwardly in a clamping stroke. This brings the plate head or pressure plate 44 against the core-plate 46 and fixedly clamps the core-plate against the core-box. As previously described, the plate 44 has a self-adjusting and equalizing action which is particularly advantageous because it insures proper clamping of the core-plate automatically and regardless of variations in shape or thickness of the core-plate 70 or in the height of the core-box within a sub-

stantial range. In ordinary practice we would consider a range of about 4" to be substantial for taking care of variations in core-box sizes. Where the variations in core-box sizes is beyond this range the supporting brackets 25 and 33 may be adjusted on the beam to accommodate the range and to obtain balance. Thus, with our invention it is not necessary to make frequent changes in adjustment of the clamping mechanism because the variations within a substantial range are automatically taken care of by our improved construction. The operator now manually swings the beam in a counter-clockwise direction to the position shown in Figure 5 and then turns the hand valve 53 to the opposite limit determined by contact of the stop member 54 against the stop 56, thus moving the valve rotor from the position shown in Figure 10 to that in Figure 9. This connects the air pressure port 71 with the pipe 51 which was originally described as leading to the bottom of the cylinder but which now is located at the top of the cylinder because the cylinder is in the inverted position shown in Figure 5. The air pressure now moves the plunger downwardly in a slow movement controlled by exhaust of the air through the restricted port 84. Simultaneously with this control movement of the hand lever 53 the operator moves the handle 71 putting the vibrator into operation. This produces slow, steady, and straight drawing of the core which, combined with the vibration, gives an exceptionally good core drawing. This lowers the core-plate 46 to the position shown in Figure 5, limited by the collar 57 striking against the adjacent end of the cylinder, as above described. The operator now removes the core-plate 46 with the finished core. The beam assembly will then be swung in a clockwise direction to the starting position and upon swinging the plunger head to the open position the machine is ready for another core-making operation.

It will be observed that according to our invention the operator stands at one position in front of the machine and he is not required to manually perform clamping and unclamping operations except as they are performed automatically in response to his actuation of a valve control lever, and that he is not required to lift heavy weights as was necessary in prior machines to lift the core-box and its supporting means in what was known as the roll-over operations. Another advantage of our invention is the elimination of adjustments incidental to variations in individual core-boxes and plates, this being effected by the plunger clamping action and the self-adjusting universal action of the clamping head. The facility with which the upper and lower assemblies may be adjusted on the beam is another feature of material advantage. The fluid controlled drawing operation is a further feature. The parts making up the assemblies are arranged to serve in a practical and satisfactory manner the objects of our invention.

While we have shown a particular embodiment of our invention, it will be understood that we do not wish to be limited thereto since many modifications may be made, and we therefore contemplate by the appended claims to cover any such modifications as fall within the true spirit and scope of our invention.

We claim:

1. In a coremaking machine, in combination, a beam structure pivotally mounted intermediate its ends to turn about a horizontal axis, a bracket mounted on one end portion of the

beam structure, a core-box holder disposed on said bracket for positively securing the core-box thereto, a head assembly mounted on the opposite end portion of the beam structure and including a cylinder and a plunger operable in the cylinder and equipped with a head adapted to engage a core-plate and clamp it against the core-box by the operation of fluid pressure in the cylinder against the piston plunger, the beam structure being rotatively movable about its support to locate the bracket either at a lower position at which the core-box is to be filled and clamped or to an upper position at which the core-box is inverted and the cylinder is underneath in a position for drawing the core downwardly, stop means for positively positioning said beam structure in the foregoing positions, a high pressure, high speed vibrator associated with the core-box holder, a valve device for directing fluid pressure to either end of the cylinder in response to valve control movements, a fluid pressure supply having a line leading to the vibrator and another line leading to the valve device, and a pressure reducing regulator in the line leading to the valve device.

2. A coremaking machine having, in combination with a core-box and a core-plate, means for positively holding the core-box and normally supporting the core-box in an upright position for making the core, a cylinder supported in a vertical position above the core-box having a piston plunger equipped at its lower end with a clamping head adapted upon the down stroke of the plunger for clamping the core-plate against the core-box, and fluid pressure control means for controlling fluid pressure to the cylinder including a valve device having a valve member operable to direct fluid pressure to the top of the cylinder for moving the plunger in said clamping stroke and operable to direct fluid pressure to the opposite end of the cylinder for moving the plunger in a core drawing stroke, means restricting the cylinder exhaust of the fluid pressure to effect a slower stroke for said core drawing than for said clamping, the described parts constituting an assembly mounted for reversal to locate the core-box in an upper inverted position in which the plunger is operable in said core drawing stroke.

3. In a machine of the character described, in combination, a beam structure pivotally mounted intermediate its ends to turn about a horizontal axis, a base plate mounted on one end portion of the beam structure, a core-box holder disposed on said base plate for positively securing the core-box thereto, a head assembly mounted on the opposite end portion of the beam structure and including a cylinder and a piston plunger operable in the cylinder and equipped with a head adapted to engage a core-plate and clamp it against the core-box by the operation of fluid pressure in the cylinder against the piston plunger, the beam structure being rotatively movable about its support to locate the base plate either at a lower position at which the core-box is to be filled and clamped or to an upper position at which the core-box is inverted and the cylinder is underneath in a position for drawing the core downwardly, the piston plunger being equipped at its lower end with a plate for clamping the core-plate, and a universal connection constructed and arranged to give to said plate a self-adjusting and equalizing action when heating it under pressure of the plunger against the core-plate, whereby said action automatically insures proper clamping of the core-plate against the core-box regardless of variations

in thickness of the core-plate or in height of the core-box within a substantial range.

4. In a machine of the character described, in combination, a beam structure pivotally mounted intermediate its ends to turn about a horizontal axis, a base mounted on one end portion of the beam structure, a core-box holder for positively securing the core-box to the base, a head assembly mounted on the opposite end portion of the beam structure and including a cylinder and a piston plunger operable in the cylinder and equipped with a head adapted to engage a core-plate and clamp it against the core-box by the operation of fluid pressure in the cylinder against the piston plunger, the beam structure being rotatively movable about its support to locate the base either at a lower position at which the core-box is to be filled and clamped or to an upper position at which the core-box is inverted and the cylinder is underneath in a position for drawing the core downwardly, and a valve device on the head assembly comprising a casing, 10 a rotary tapered valve fitting in the casing, a hand lever for rotatively moving said valve, a fluid pressure supply lead to the casing, a slow exhaust opening and a fast exhaust opening in the casing, port communications between the casing and opposite ends of the cylinder, and ports in the valve and in the casing for communicating said fluid pressure supply with the cylinder and with the respective exhaust ports to effect a fast clamping stroke of the plunger and a slow core drawing stroke.

5. In a machine of the character described, in combination, a beam structure pivotally mounted intermediate its ends to turn about a horizontal axis, a base mounted on one end portion of the beam structure, a core-box holder for positively securing the core-box in a pre-selected position, a head assembly mounted on the opposite end portion of the beam structure and including a cylinder and a piston plunger operable in the cylinder and equipped with a head adapted to engage a core-plate and clamp it against the

5
